FLOW CONTROL OF FUEL

Clesson E. Mason, Foxboro, Mass., and Ralph A. Rockwell, Cranford, N. J., assignors to The Foxboro Company, Foxboro, Mass., a corporation of Massachusetts

Application September 14, 1939, Serial 294,931

11 Claims. (Cl. 158—36.3)

This invention relates to oil burning systems utilizing mechanical atomizers for atomizing fuel oil burned and more particularly to a method and apparatus for varying the rate of fuel consumption while maintaining efficient atomization.

The various types of burners used in the oil firing art may be roughly classified in two groups. In one type of burner the heavy fuel oil used for firing industrial equipment such as furnaces, boilers, and the like, is dispersed or atomized by mixing a pressure fluid such as steam with the mass of oil and forcing the mixture of steam and oil through a nozzle to form a fine spray. In the other type of burner the fuel oil is atomized by mechanical means alone and it is this type of burner with which the present invention deals. In one type of mechanical burner which will be here discussed for purposes of illustration the oil is forced into a cylindrical chamber near the tip of the burner just in back of its discharge nozzle in a direction which is tangential to the cylindrical wall of the chamber and is thus given a whirling motion to produce centrifugal force which causes the oil when forced from the chamber through the discharge nozzle to form a fine conical spray. The combustion efficiency of the burner depends in large measure on the degree of atomization produced and hence it is desirable that oil be supplied to the tip chamber at such a rate as to maintain an adequate whirling or centrifugal action in the chamber.

The present invention is directed to an improved method and apparatus for manually or automatically controlling the quantity of oil burned by a mechanical burner of this general character and at the same time maintaining the desired burner efficiency.

As the oil firing art has developed one of the problems encountered has been the difficulty of obtaining a mechanical burner having a sufficient degree of rangeability, that is, a burner which atomizes oil at rates of flow varying from a relatively low rate to a relatively high rate, and which at the same time produces substantially the same kind of spray for the different rates of flow. Several ways have been proposed for solving this problem. According to one system, as described in U. S. Patent No. 1,628,424 to Peabody, oil is supplied to the burner under pressure but not at a constant rate of flow and a return line is provided from the burner either to the pump intake or to the oil source. When the return line is closed off all the oil supplied to the burner tip chamber flows out through the discharge nozzle of the burner and under this condition the tangential passages are supply-

ing the oil to the burner tip chamber against the maximum static pressure in the burner tip chamber. A valve is provided in the return line and as the valve is opened it permits part of the oil supplied to the burner to leave the burner through the return line and thus reduces the static pressure in the burner tip chamber. This system has the disadvantage that as the valve in the return line is opened and the pressure in the chamber is reduced the flow through the tangential passages of the burner increases, although the output of the burner has been decreased by opening the valve. This increased flow changes the characteristic of the spray.

15 Aside from this disadvantage such a system of varying the oil burner output has other inherent limitations and disadvantages in operation which militate against its use with automatic control apparatus to satisfactorily correlate rate of oil burning with the behavior of the temperature being controlled.

20 Another attempt to satisfy the problem of maintaining the desired whirling motion of the oil in the burner tip chamber for varying rates of fuel consumption is disclosed in U. S. Patent No. 1,824,952 to Graham. In this disclosure, as in Peabody, Graham varies the quantity of fuel sprayed by changing the opening of a valve in a return line and in addition provides differential pressure control which is intended to maintain a constant pressure difference between the burner input line and the return line. Thus, as the static pressure in the burner tip chamber is reduced by opening the valve in the return line the supply pressure is reduced an equal amount which tends to maintain constant the amount of fuel supplied to the burner tip chamber.

25 Inasmuch as this system employs a variable restriction in the return line to effect variations in the rate of fuel consumption it has the same disadvantages when used in connection with automatic control as those described above in connection with the Peabody system.

30 In any type of mechanical atomizing burner using a return flow the quantity being sprayed is the difference between the rate of oil flow to the burner and the rate of oil flow returned from the burner. Therefore, any quantity change in either the rate of oil flow to the burner or the rate of oil return must appear as the same quantity change in the fuel discharge rate, and since there is often a relatively high ratio of the rate of oil flow to the burner or the rate of oil flow returned from the burner, to the quantity of oil sprayed, percentage change in either supply or

return flow will appear as a magnified percentage change in the fuel discharge rate. Thus, it is often impractical to attempt to control the amount of oil sprayed by attempting to control the flow of the rate of fuel flow either to or from the burner.

In the present invention these disadvantages are overcome and a system is provided which is adapted to automatic control applications because it provides for the desired correlation of the fuel consumption with the demands of a control instrument which in turn is responsive to the behavior of the controlled temperature. Further, the present invention provides for the removal of one or more burners, for cleaning or repair, from a plurality of burners connected in parallel without disturbing the total fuel consumption at the time the burners are removed.

In the accompanying drawings,

Figure 1 shows a diagrammatic layout of a system embodying the invention; and

Figure 2 shows diagrammatically the cross-section of a mechanical burner of the type described; and

Figure 3 is a section taken along the line 3—3 of Figure 2.

Referring to Figure 1, the numeral 1 indicates the combustion space of a furnace 2, which may be equipped with a plurality of mechanical atomizing burners 3 connected in parallel and which may be of the type shown diagrammatically in Figure 2.

Referring to Figure 2, the burner 3 includes an inner cylindrical conduit 75 and an outer concentric conduit 76. Oil flowing to the burner passes through an inlet connection 77 and the annular space between the conduits 75 and 76 to the burner tip 78. At the burner tip the oil flows through a plurality of small passages or jets 79 to a cylindrical burner tip chamber 80. The axes of the passages 79 are approximately tangent to the cylindrical inner surface of the chamber 80 so that the oil is given a rapid whirling motion as it enters this chamber. A portion of the whirling mass of oil in the chamber 80 flows out of the discharge orifice 81 and is atomized to form a fine conical spray whereas the remainder of the oil passes through a passage 82 to the inner conduit 75 and thence through the burner outlet or return connection 83. The rate at which oil is discharged through the orifice 81 may for practical purposes be considered as depending upon the static pressure in the chamber 80.

Referring again to Figure 1, suitable ducts 4 may be provided to admit air to the combustion space 1. A constant volume pump 5, such as a motor driven gear pump, is connected by a line 6 to the burners and serves to supply oil to the burners. Since for the reasons pointed out above it is desirable to supply oil through the tangential jets of the burners at a constant rate regardless of the burner output, a constant volume pump is preferably used to pump the oil to the burners. However, since it may often be impractical to select a constant volume pump of the exact capacity or one with an adjustable speed to supply the oil to the burner at the rate desired, provision is made by the present invention for use of a constant volume pump of larger capacity than that required and a by-pass 5a having a manually operable valve 5b is connected across the output line 6 and the suction side of the pump. As will be described, the net output of the pump to the burners may be adjusted

by adjusting the valve 5b and for each adjustment the rate of oil flow through the tangential jets remains substantially constant regardless of the output of the burners.

That portion of the oil supplied to the burners which is not discharged into the combustion space 1 passes without restriction through the return line 7 to the suction of the pump 5. Thus, the lines 6 and 7, the pump 5, and the burners 3 form a closed circulating system.

Each of the burners 3 is provided with a by-pass line 3a containing a restriction 3b. The restriction 3b is constructed in such a manner as to have the same flow capacity and preferably the same flow characteristic as the tangential jets 79 of the burner. Occasionally it becomes necessary to take one of the burners out of service to clean it or for other purposes and in such a case valve 3d in branch line 3e and valve 3f in branch line 3g are closed and valve 3c in by-pass line 3a is opened. Due to the presence of the restriction 3b in the by-pass line 3a the same quantity of oil will flow through the branch lines 3g when the burner is not in service as when the burner is in service. A further advantage resulting from the use of the by-pass 3a is that since a flow of oil through the branch lines is maintained when the burner is out of service, the viscous oil frequently used as a fuel will not cool and congeal in the branch lines. For the same reason the by-pass 3a should be short and located in the block of the burner so that it will stay hot. Although the output of the burners remaining in service increases, the quantity of oil flowing to the burner tip chambers of the burner or burners which remain in operation will be maintained constant and hence the spray characteristic of the remaining burners and their efficiencies will be the same as before. As the description proceeds it will become apparent that the burner or burners left in service will automatically assume the load normally carried by the burner taken out of service, and the quantity of oil discharged into the combustion space 1 will also remain constant.

Referring to the lower left-hand corner of Figure 1, there is shown an oil storage tank 8 from which oil to make up the oil discharged from the burner nozzle flows to the circulating system through a pipe 9 under the pressure supplied by a suitable positive displacement pump 10 in the line 9 between the tank 8 and the pump 5. When the fuel being burned is a heavy residual fuel oil suitable heating means may be provided at various points in the system to maintain the fuel in a desirably fluid condition.

Since oil is a non-compressible fluid and the circulating system is completely filled with oil, the rate at which oil is discharged into the combustion space 1 by the burners 3 is precisely equal to the rate of flow of oil in line 9, and in accordance with the present invention the flow of oil in the line 9 is metered and controlled to control the discharge of the oil from the burners. This metering and control of the oil flow in the line 9 is accomplished by a flow controller, generally indicated at 13, which includes an orifice 14 in the line 9. The operating means of the flow controller is a pneumatic pressure which operates a valve 12 in a liquid return line 11. The valve 12 serves as a variable restriction in the line 11 to vary the flow in the line 9. The flow controller thus acts in response to the pressure difference across the orifice 14 to maintain the flow through the line 9 at a desired value

which may be considered as the control point of the flow controller.

This desired value or control point may itself be varied or set up or down by a temperature controller, generally indicated at 20. The temperature controller is responsive to a temperature sensitive element 60 in the furnace 2 and the operating means of the temperature controller is a pneumatic pressure the value of which determines the setting of the control point of the flow controller 13. Thus, with this system an accurate correlation between the behavior of the temperature of the furnace 2 and the oil burner is obtained.

The orifice meter shown is essentially a U-tube comprising a high pressure leg 15, a low pressure leg 16, and a pipe 17 connecting the two. The meter is partially filled with mercury, the level of the mercury in the high pressure leg 15 being indicated at 15a, and the level of the mercury in the low pressure leg 16 being indicated at 16a. The high pressure leg 15 communicates with the pressure in line 9 upstream of the orifice 14 through a line 19, whereas low pressure leg 16 communicates with pressure downstream of the orifice 14 through a line 22. Suitable seals (not shown) may be used when necessary to prevent the fuel flowing in the line 9 from entering the meter piping or chambers.

Floating on the surface 15a of the mercury in high pressure leg 15, there is a float 28 provided with a vertical mast 29 connected by a chain 30 to an arcuate member 31. The arcuate member 31 is mounted on a lever arm 32 which is secured to and supported by a rotatable shaft 33 mounted in a suitable bearing 34 located in the wall of the high pressure leg 15. The shaft 33 carries a lever arm 35 located outside of the high pressure leg 15. The construction is such that if, for example, the differential across the orifice plate 14 increases, mercury flows from the high pressure leg into the low pressure leg to balance the pressure differential increase, the level 15a of mercury falls carrying with it the float 28, mast 29, and arcuate member 31, and the external lever arm 35 will be rotated in a clockwise direction, as shown. If, on the other hand, the differential across the orifice plate 14 decreases the lever arm 35 will be rotated in a counter-clockwise direction. Thus, the arm 35 is angularly positioned in response to the value of the differential pressure across the orifice plate 14.

The position of the lever arm 35 is used to vary the pressure on the valve 12 and so position it in the following manner. At its lower end the lever 35 is connected by a link 36 to flapper 40, and thus the flapper is positioned in accordance with the differential pressure across the orifice plate 14. The position of the flapper is translated into a proportional pneumatic pressure for operating valve 12 by follow-up mechanism that will now be described.

Cooperating with the flapper is a movable nozzle 41. A portion of the air from a supply line 42 passes through a branch line 43, a restriction 44, and branch line 45 to the nozzle 41 and to a bellows 51 operating a valve plunger 47 of a double-seated valve 46. The double-seated valve 46 regulates the pressure in a line 49 connected to the control valve 12 and in a line 50 connected with a bellows 53 which forms a part of the follow-up mechanism. The operation of the double-seated valve is such that as the plunger 47 moves to the left, as shown in the drawings, the pressure in lines 49 and 50 increases and

as it moves to the right the pressure in lines 49 and 50 decreases. The operation of the valve 46 is such that as the flapper 40 and nozzle 41 approach one another, pressure tends to build up in the line 45, expanding the diaphragm 51, thus moving plunger 47 to the right, as shown, and decreasing pressure in lines 49 and 50, whereas as the flapper 40 and nozzle 41 recede from one another pressure in line 45 tends to decrease, contracting bellows 51 to move plunger 47 to the left, as shown, thus increasing pressure in lines 49 and 50.

Nozzle 41 is positioned by link 59 which is in turn positioned by a compound lever 56 and in the arrangement shown link 59 is positioned through compound lever 56 by either or both of the bellows 53 and 67 acting through links 55 and 69, respectively. The bellows 53 and 67 are rigidly secured at one end and at their other end move against the action of springs 54 and 68 to move links 55 and 69 which are pivotally connected to the compound lever 56 at the lower end 58 and upper end 57 of the lever 56.

The line 59 communicates with the interior of bellows 53, and if the pressure in bellows 67 is maintained at a constant value changes in pressure in line 50 will produce corresponding changes in the position of the nozzle 41. Since a static balanced pressure condition would require the plunger 47 to be in some mid-position between its two seats, the follow-up mechanical arrangement will require the nozzle to be substantially tangent to the flapper, and since the pressure in lines 49 and 50 also governs the opening of control valve 12 which in turn influences the flow through the orifice 14 and hence the position of the flapper 40, a static pressure and a static flow condition requires that the flow be proportional to the assumed position of pivot 51 and hence proportional to the pressure existing in bellows 67.

The control point of the flow controller 13, as described above, may be varied by varying either manually or automatically the pneumatic pressure in the bellows 67 or the position of the pivot 57. If the pressure in bellows 67 is increased the initial operation is to move nozzle 41 clockwise a proportionate amount, thus separating nozzle 41 from flapper 40. This initial operation causes the pressure in lines 49 and 50 and in bellows 53 to increase which will retard or reverse the clockwise movement of nozzle 41 and at the same time increase the flow through the orifice plate 14. The increased differential pressure across orifice 14 will rotate flapper 40 in a clockwise direction and a new static pressure and static flow condition will be established such that the increase in flow is proportional to the increase in pressure in bellows 67. If the pressure in bellows 67 is decreased the operation of the parts is reversed and flow in the line 9 is decreased in proportion to the decrease in pressure in bellows 67.

In the present embodiment a pneumatically operated temperature controller is used to reset the control point of the flow controller 13 in the manner described above and hence control the amount of oil sprayed by the burners 3 in response to variations in the temperature of the furnace 2. The temperature controller 20 will now be described more in detail.

The temperature sensitive element 60 in the furnace 2 is connected by a flexible tube 61 with a helical responsive element 62 which, through a link 63, positions a flapper 64 in accordance

with the value of the measured temperature. The position of the flapper 64 is translated into a pneumatic pressure in the line 66 in a manner similar to that described in connection with the flow controller 13.

Cooperating with the flapper 64 there is a variable nozzle 65. A portion of the supply air passes through a restriction 74 to the nozzle 65 and to a bellows 73 operating the plunger of a double-seated valve 72. The double-seated valve 72 regulates the pressure in line 66 and a bellows 70 which, like bellows 53, operates to maintain the nozzle 65 substantially tangent to the flapper 64 and the behavior of the pressure in line 66 is inversely proportional to the behavior of the temperature in the furnace 2. The pressure in line 66 is conducted to bellows 67 of flow controller 13 through a line 71.

The operation of the apparatus as a whole is as follows:

If, for example, the load on the furnace decreases so that the present amount of fuel being burned by the burners 3 causes the temperature measured by element 60 to start to rise, the flapper 64 rotates in a clockwise direction, thus increasing the pressure in bellows 73, reducing the pressure in line 66 and in bellows 70 to cause the nozzle to follow the flapper. This reduction in pressure is transmitted through line 71 to bellows 67 and the resulting initial counterclockwise movement of nozzle 46 increases the pressure in bellows 51 to cause the double-seated valve 46 to decrease the pressure in bellows 53 to hold the nozzle 46 tangent to the flapper 40. The resulting decreasing pressure in line 49 opens valve 12 and decreases the flow through orifice 14 until the change in flow in line 9, and thus in the amount sprayed by the burners, is proportional to the change in pressure in bellows 67. The resulting proportionate fuel reduction tends to prevent further increase of the measured temperature, and the action continues until a new static temperature, new operating air pressures, and a new flow balance are reached. If the load on the furnace 2 increases so that the present amount of fuel being burned by the burners causes the temperature of the furnace to drop, by similar and opposite reactions the flow of fuel is increased until a new static temperature, new operating air pressures, and a new flow balance are reached.

Thus, the flow of fuel is positively correlated with the operating means of the temperature controller. It should be understood that the control characteristics of the temperature controller 20 as well as of the flow controller 13 may be changed from that shown in the drawings by adding other instrumentalities to overcome lag complications in the process being controlled.

It is apparent that in order to maintain a uniform spray characteristic with varying quantities of fuel sprayed it is necessary to maintain a uniform flow through the tangential jets of each burner. Since in the system embodying the present invention there are no appreciable restrictions in the return line under any condition of flow in the return line the pressure on the suction of the pump 5 is substantially equal to the static pressure in the burner tip chamber. Therefore, the pressure drop across the by-pass valve 5b is substantially equal to the pressure drop across the tangential jets of the burner. Furthermore, the pressure drop across the tangential jets and across the by-pass valve 5b is constant for all rates of flow of make-up oil and

hence for all burner discharge rates. The reason for this is that the pump 5 is a constant volume pump which is operating on a non-compressible fluid and so the sum of the flows through the

5 by-pass line and the tangential jets is equal to the pump output and is constant. Further, since the pressure drops across the by-pass valve and the tangential jets are always equal, the ratio of the flow through the by-pass line to the flow through the tangential jets is constant. Therefore, the rate of flow through the tangential jets is constant and is unaffected by variations in the rate of flow of make-up oil.

Since many embodiments might be made in 15 the above invention, and since many changes might be made in the embodiment above described, it is to be understood that all matter hereinbefore set forth or shown in the accompanying drawings is to be interpreted as illustrative only and not in a limiting sense.

We claim:

1. The method of regulating the temperature of a furnace fired by an oil burner of the oil recirculating type utilizing mechanical means to 25 atomize the oil burned, which comprises establishing a constant volume flow from a pump to said burner at a rate in excess of the rate at which oil is atomized for burning by said burner, recirculating excess oil not atomized back to said pump in a closed circulating system, supplying make-up oil from a source of oil to said circulating system and controlling the rate of flow of make-up oil to said system at a point intermediate said source and said circulating system 30 and in response to a variable condition influenced by the temperature in said furnace.

2. Method of regulating the temperature of a furnace fired by an oil burner of the oil recirculating type utilizing mechanical means to atomize the oil burned, which comprises pumping oil into said burner at a constant volume rate in excess of the rate at which oil is atomized for burning by said burner, recirculating excess oil not atomized back to said pump in a closed circulating system, supplying make-up oil to the low pressure side of said circulating system, metering the flow of said make-up oil and using a variable condition influenced by temperature variations of said furnace to vary the metered flow to maintain said temperature at a substantially constant value.

3. Method of controlling the oil sprayed by a mechanical atomizing burner of the oil recirculating type, which comprises establishing a constant volume flow from a pump to the burner, returning an unrestricted flow of excess oil not sprayed back to the pump, supplying make-up oil to said pump, measuring the quantity of the make-up oil thus supplied, and controlling the amount of oil sprayed by regulating the amount of make-up oil in response to variations in the measured quantity of make-up oil.

4. Method of controlling the burning characteristics of the oil flame of a mechanical atomizing burner of the oil recirculating type, which comprises establishing a constant volume flow of oil to the burner in excess of the quantity of oil burned, recirculating excess oil not burned to establish a closed system, supplying make-up oil 65 to the said system, measuring the rate at which make-up oil is supplied to said system, and controlling the amount of oil burned by controlling the make-up oil supplied in response to variations in the measured rate of flow of make-up oil.

5. Apparatus for controlling at a control point

a condition of a furnace fired by an oil burner of the oil recirculating type utilizing mechanical means for atomizing the oil burned, comprising, in combination with said burner, an oil circulating system including a constant volume pump for supplying oil to said burner at a constant volume rate in excess of the rate at which oil is atomized by said burner, and means for recirculating excess oil to said pump, means including a conduit for supplying make-up oil to said system, a flow controller associated with said conduit for controlling the rate of flow of make-up oil supplied through said conduit to said circulating system, and means for regulating said flow controller in response to the said condition of said furnace.

6. The method of regulating the temperature of a furnace fired by an oil burner of the oil recirculating type utilizing mechanical means to atomize the oil burned, which comprises establishing a constant volume flow from a pump to said burner at a rate in excess of the rate at which oil is atomized for burning by said burner, recirculating excess oil not atomized back to said pump through an unrestricted passage to form a closed circulating system, supplying make-up oil from a source of oil to said circulating system, and controlling the rate at which make-up oil is supplied to said system at a point intermediate said source and said circulating system and in response to a variable condition influenced by the temperature in said furnace.

7. A method for controlling the burner output of a plurality of mechanically atomizing oil burners of the oil recirculating type connected in parallel to the discharge of a pump, each burner being also connected through an unrestricted return line with the intake of the said pump to return excess oil not burned and each burner having a predetermined resistance coefficient to the flow of oil therethrough, comprising pumping a constant volume of oil to said burners regardless of the burner output, returning oil not burned through said unrestricted return line, supplying oil to the intake side of said pump to make up the oil burned, and inserting in the return line of a burner taken out of service a restriction having substantially the same flow coefficient as the burner removed whereby the volume of oil pumped to each burner remaining in service remains the same, and the flame characteristic of the burners remaining in service remains substantially the same.

8. Apparatus for regulating the temperature of a furnace fired by an oil burner of the oil recirculating type using mechanical means to atomize the oil burned, comprising, in combination, a closed oil circulating system including one or more burners, a constant volume pump provided with a by-pass containing a variable restriction, an oil supply line for supplying oil to said burners from said pump, and an oil recirculating line providing an unrestricted passage for flow of oil from said burners to said pump, a source of oil, means for supplying make-up oil from said source to said system, and means responsive to the temperature of said furnace for controlling at a point intermediate said source of oil and said circulating system the rate at which make-up oil is supplied to control the rate at which oil is atomized by said burner.

9. Apparatus for regulating the temperature

of a furnace fired by oil burners utilizing mechanical means to atomize the oil burned and wherein oil is supplied to said burners at a volume rate in excess of the rate at which oil is atomized by said burners, comprising, in combination, a closed oil circulating system including a constant volume pump for circulating oil in said system, one or more burners, an oil supply line for supplying oil to said burners, and an oil recirculating line for recirculating oil from said burners to said pump, means for supplying make up oil to said circulating system, means for measuring the quantity of make up oil supplied, and means responsive to the temperature of said furnace and to the measured quantity of make-up oil for controlling the rate at which make up oil is supplied to control the rate at which oil is atomized by said burners.

10. In apparatus for controlling the quantity of oil burned by oil burners utilizing mechanical means to atomize the oil burned and wherein for efficient atomization oil is supplied to said burners at a constant volume rate in excess of the rate at which oil is atomized by said burners, in combination, a supply line and means for supplying oil to said line at a constant volume rate, a plurality of burners connected in parallel to said line and each provided with a plurality of tangential jets providing restriction to flow of oil therethrough, and means for cutting out one of said burners from service without changing the total restriction to oil flow through the system, said means including an oil by-pass line around each of said burners containing a predetermined fixed restriction having the same flow capacity as the tangential jets of said burner to permit continual flow past said cut out burner through a fluid path having the same flow resistance as the jets of said burner, whereby the volume rate of oil flow to each of the remaining burners remains unchanged.

11. In apparatus for controlling the quantity of oil burned by oil burners utilizing mechanical means to atomize the oil burned and wherein for efficient atomization oil is supplied to said burners at a constant volume rate in excess of the rate at which oil is atomized by said burners, in combination, a closed oil circulating system including a constant volume pump for circulating oil in said system, an oil supply line for supplying oil to said burners, a plurality of burners connected in parallel to said line and each provided with a plurality of tangential jets providing restriction to flow of oil therethrough, and an oil recirculating line for recirculating oil from said burners to said pump, means for supplying make up oil to said circulating system, means for controlling the rate at which make up oil is supplied to said system to control the rate at which oil is atomized by said burners, and means for cutting out one of said burners from service including an oil by-pass line around each of said burners containing a predetermined fixed restriction having the same flow capacity as the tangential jets of said burner to permit continual flow past said cut out burner through a fluid path having the same flow resistance characteristics as the jets of said burner, whereby the volume rate of oil flow to each of the remaining burners remains unchanged.
